James Darrow

Letter Patent (Sept. 8, 1834)

1. The details of each of the three Letters Patent and making part of the
specifications, drawings, and models, in the name of the same James Darrow
and of his assignee, the Hill Carr Company.

2. I claim this patent to all who will come to know that James Darrow
in the State of Rhode Island have invented a new and
useful improvement in a Mill Carr, and that the following is a full
and clear description of the same and the improvement by me as
well as the mode of construction thereof. In the Mill Carr as
shown in the drawing, the Mill Carr is attached to the bottom of Hill Carr to protect them and
to prevent them from running away.

3. The Mill Carr is about one half of an inch or more in width
and is made of a coarse or rough plane wood. It has a thin
beam or puncheon and projecting from its inner edge by which
it is attached to a car, with a fast or otherwise. The upper
beam or puncheon is about the same height above Mill Carr as the car is wrought
and is made of the same material as the Mill Carr.
